SAFETY MECHANISM FOR CENTRIFUGAL DRIERS

Gunnard A. Oberg, Celoron, N. Y., assignor to
 Blackstone Corporation, Jamestown, N. Y., a
 corporation of New York

Application January 15, 1949, Serial No. 71,095

5 Claims. (Cl. 200—52)

1

This invention relates to improvements in a device in which a rotatable receptacle is provided for centrifugally drying articles contained therein. More particularly, the invention relates to a safety mechanism intended to stop rotation of a rotating receptacle should unevenly distributed articles or mechanical defect create or set up vibrations that are in excess of a safe, predetermined limit. To more clearly illustrate the usefulness of the invention, it is shown as consisting of a mechanism that is applicable to, or may be used in connection with a combined washing and drying machine or other centrifugal drying devices. This mechanism includes a switch that is in the circuit of the motor which operates the receptacle, and trigger means for moving the switch into an off-position at any time the receptacle vibrates beyond a predetermined extent.

It is well known that centrifugal clothes dryers frequently become damaged or rendered unsafe to operate due to an operator's failure to more or less uniformly distribute articles of clothing about the receptacle, prior to commencing the spinning or drying operation. With only a few clothes in the receptacle, little or no vibration is likely to occur during a spinning operation. However, with a normal load in the receptacle, it is desirable that the clothes be rather evenly distributed to prevent an unbalanced condition during high speed rotation. Generally, the need for distributing clothes in such a receptacle usually only occurs when the receptacle is being used primarily as a spinner dryer. In many combination washing and drying machines, the clothes, following a washing operation, are sufficiently distributed to preclude excessive vibration during the succeeding spinning operation.

It is an object of the present invention to provide a mechanism that will function to shut off a spinner drying machine when said machine is operating under improper load conditions.

It is another object of the invention to provide a mechanism that is operatively associated with a suspended support for the rotatable receptacle of a drying machine.

A further object of the invention lies in the provision of a switch mechanism that operates to shut off the motor of a spinner drying machine when vibration transmitted to the support of the spinning receptacle reaches or exceeds a predetermined limit.

Other objects and advantages of the invention will be more fully understood from a consideration of the following specification, taken in con-

2

junction with the accompanying drawings; and in which

Fig. 1 is a front elevational view of a device for spin drying articles, parts being broken away to disclose the location and operating association therewith of the structure of the invention;

Fig. 2 is an enlarged front elevational view of the invention in the operative position as shown in Fig. 1;

Fig. 3 is a top plan view of the structure of Fig. 2, the mechanism being shown in set position; and

Fig. 4 is a view similar to Fig. 3, showing the mechanism following operation.

Referring more particularly to the drawing, the reference numeral 10 is employed to generally designate a device for washing and drying clothes. The invention is shown associated with such a device although it will be understood from

the following description that it is equally applicable to any type of centrifugal dryer wherein the mounting means for the rotatable receptacle is resiliently supported. In the present instant, the device includes a cabinet 11, access to which 20 may be had through an opening closed by a cover 12. Within the upper portion of the cabinet is located what may be termed a splash ring 13. Within the ring 13 is located a rotatable receptacle 14 which is carried by a suitable support 16. This support includes a sleeve or housing 17, through which a drive shaft projects and, on its upper end, mounts the receptacle 14. The drive shaft, of course, is connected with an electric motor which provides operative power for all functions of the device. The lower portion of the support, for purposes of illustrating the invention, may consist of a spider 18, having terminals 19 that, through suitable resilient blocks 21, are secured to a base

22 by means of bolts 23. From the description thus far it is evident that any vibration of the receptacle 14 during a spinning operation will be transmitted to the support 16. In view of the fact that the device 10 is shown to be a combination washing and drying machine, there is shown a water pump 24 which is mounted on a lower portion of the support 16. The sole purpose of showing and describing the water pump is due to the fact that the mechanism 40 of the invention, in the present disclosure, is found to be more conveniently operatively associated therein. It will, however, be understood that the shut off mechanism may be equally applicable to any other part of the resiliently 45 mounted support for the rotatable receptacle.

More specifically, the invention includes a switch box 26 which is suitably mounted on a portion of the base 22. This switch is in the electrical circuit for the motor (not shown) that operates the receptacle 14. Extending from the box is a swingable switch arm which terminates in a knob 27. A bracket 28 is suitably secured to the base 22 and at one end includes an upstanding arm 29 that is provided with a slot 31. At its other end the bracket 28 includes an upwardly and laterally offset arm 32. An angle plate 33 is attached to the bracket base and corresponds in opposed relationship to arm 29. The upstanding portion 34 of this plate is slotted as at 36. A 15 slidable bar 37 projects through slots 31 and 36. At one end this bar is formed with an arm 38 which is in the plane of the knob 27 and, as shown in the drawing, is engaged with said knob when the switch is in the "on" position. Projecting through an opening in the bar 37 is a 20 split pin 39. One wing 41 of this pin is bent against the bar to prevent displacement. The other wing serves as an abutment for one end of a compression spring 42 which is shown to encircle the bar throughout a considerable portion of its length. The other end of this spring abuts the arm 29 of the fixed bracket 28.

Mounted on the offset arm 32 of the bracket 28 is a pivotal member 43. This member includes a short arm 44 which terminates in an upstanding flange 46. A threaded opening in this flange receives a threaded contact member 47 which may be locked in any position of projection beyond said flange by means of a nut 48. The member 43 includes a long arm 49 which terminates in an offset finger 51. The end of the finger 51 is connected with the head of pin 39 by means of an expansion spring 52. Adjacent the finger 51, arm 49 is provided with a shoulder 53 which, in one position of the member 43, serves as an abutment for an end of bar 37. As may be seen in Figures 3 and 4 of the drawing, the member 43, although carried by a fixed portion of the device, is in such proximity with the water pump 24 as to enable adjustment of the member 43 into close proximity with the most laterally extending portion of said pump.

The structure of the invention having been described, the following is set down to disclose the operative advantages. The device, as shown in Figures 1, 2 and 3, is in set position, the switch 26, in the receptacle motor circuit, being in the "on" position. Referring more particularly to Figure 3, it will be noted that member 43 has been turned to bring the end of member 47 into close proximity with a lateral extension or lug on the water pump 24. It will also be noted that member 43, in this position, is in alignment with bar 37. Due to the fact that spring 42 has been compressed, one end of said bar is in pressure contact with shoulder 53 and spring 52 is under expanded tension. If, as brought out in the explanation of the advantages of the invention, an operator of the device attempts to spin dry articles that have been unevenly distributed about the receptacle, considerable vibration will occur. Since the support 16 is resiliently mounted on the base of the device, this vibration, if excessive, will be directly transmitted from the receptacle to the support. Of course, the pump 24, being carried by the support, will also vibrate and such vibration will cause a lateral shifting of the pump at least to an extent suggested in Figures 3 and 4 of the drawing. Lateral movement of the pump causes

it to engage and move member 47, thus swinging member 43 about its pivotal support and breaking the straight line condition of member 43 and bar 37 under compulsion of spring 42. 5 As soon as shoulder 53 clears bar 37, said bar moves in a lateral direction, and arm 38 thereof moves knob 27 of the switch into "off" position. Thus, regardless of the fact that the motor for the receptacle is still intended to be operating, it will immediately cease and the receptacle come to a stop due to the fact that the motor circuit has been broken by operation of switch 26.

Although applicant has shown and described only one form of his invention and its application to a particular type device, it will be understood that the invention is fully applicable to a variety of centrifugal devices in its present form or with simple modification, and that such modification and use are within the spirit and scope of the invention as set out in the annexed claims.

Having thus set forth my invention, what I claim as new and for which I desire protection by Letters Patent is:

1. In a device having a rotatable receptacle mounted on a resilient suspension and including electrically operated means for rotating said receptacle; a shut-off mechanism comprising a switch in the circuit of said means, a contact member mounted for movement into either of two positions and in one of said positions being in close proximity with a part carried by said suspension, and spring actuatable means connecting said member with said switch, said member being moved into the other of said positions by contact of said part therewith to render said spring means operable to actuate said switch to open the circuit of said electrically operated means.

2. In a device having a rotatable receptacle mounted on a resilient suspension and including electrically controlled means for rotating said receptacle; a shut-off mechanism comprising a switch in the circuit of said means, a contact member mounted for movement into either of two positions and in one of said positions being in close proximity with a part of said suspension, a slidable bar operatively associated with said switch, means normally urging said bar in a direction to move said switch into one position, said member, when in the position of proximity with said part, serving to prevent movement of said bar.

3. In a device having a rotatable receptacle mounted on a resilient suspension and including electrically controlled means for rotating said receptacle; a shut-off mechanism comprising a switch in the circuit of said means, a contact member mounted for pivotal movement into either of two positions and in one of said positions being in close proximity with a part on said suspension, a slidable bar operably associated with said contact member and operable to actuate said switch, and spring means urging said bar into abutment with said member when in said one position.

4. In a device having a rotatable receptacle mounted on a resilient suspension and including electrically operated means for rotating said receptacle; a shut-off mechanism for said means comprising a switch in the circuit of said means, an operable arm extending from said switch, a pivotal member, spring actuatable means for setting said member in a position of near proximity with a part of said suspension, said spring actuatable means being engaged with said arm and operable to open the circuit of said means when

said member has been contacted and moved by said suspension part.

5. In a device having a rotatable receptacle mounted on a resilient suspension and including electrically operated means for rotating said receptacle; a shut-off mechanism for said means comprising a switch in the circuit of said means, a pivotal member, a slidable bar engaged with and movable to open said switch, spring means manually operable to set said member in a posi-

tion of near proximity with a part of said suspension and said bar in a position to close said switch.
